HAIR CURLER

Nathan L. Solomon, Mt. Vernon, N. Y.

Application April 26, 1938, Serial No. 204,379

25 Claims.

(Cl. 132—33)

The present invention is directed to an improved and serviceable hair curler including as its broad and dominating object the provision of novel and simplified means for transferring a curl therefrom to be automatically threaded onto one leg of a normally closed hair pin held diverged and in a waiting relation on a rotatable support at one end of the curler. Other objects, advantages, and features of the invention will be apparent from the following detailed description viewed in the light of the accompanying drawing in which:

Fig. 1 is a perspective view of the hair curler according to my invention particularly showing a hair pin supported at one end of the curler and in an open and waiting relation for the curl to be wound.

Fig. 2 is a view similar to Fig. 1 however illustrating a curl wound about the curler and ready to be transported onto the waiting hair pin.

Fig. 3 is a longitudinal sectional view of the hair curler wherein the hair clamping complements of the curler are shown closed and the curl ejector is in its normally retracted position.

Fig. 4 is an enlarged transverse sectional view on the line 4—4 of Fig. 3.

Fig. 5 is a fragmentary view of Fig. 4 however illustrating the curl ejector releasing the clamping pressure previously exerted on the curl by the cover preparatory to automatic threading of the curl onto the opened hair pin by the ejector.

Fig. 6 is a fragmentary view of Fig. 5, showing the manner in which the curl formed has been transported and threaded on one shank of the open hair pin and further illustrating the manner in which the hair pin has been displaced longitudinally of the curler on receiving the curl.

Fig. 7 is a perspective view of the ejector and Fig. 8 is an enlarged fragmentary view of the curler illustrating the hair pin control housing or shell containing the normally compressed helicoidal spring.

Illustrative of the embodiment disclosed, the hair curler is generally denoted H and embodies a cylindrical tube or complement 10 carrying a suitable upset fulcrum pin 11 on which a hair clamping complement or cover 12 is pivotally connected.

Slidably mounted within bore 13 of tube 10 is a cylindrical housing or runner 14 of the curl ejector broadly designated 15 which also embodies an outside cylindrical knurled sleeve or collar 16 which is slidably mounted outside of the tube 10 and which is provided with an annular flange

17 having a gap or cutaway portion 18 to receive the intermediate inclined cam portion 19 of the pivoted cover when the ejector is in its fully and normally retracted position shown in Fig. 2.

The pivoted hair clamping cover 12, may be said to be longitudinally offset in that the rear and front portions thereof are out of alinement although integrally merged with the inclined cam part or shoulder 19 which constitutes a stop cooperating with rim 20 of the exterior bushing or sleeve 16 to prevent accidental movement of the latter longitudinally of the tube in one direction towards the front end of the tube when the pivoted cover is held fully closed by spring 21 interposed between the rear end of the cover and the closed end 22 of the tube 10 and when, of course the rear end 23 is contiguous to the pivoted ears 24 of the cover.

According to the invention, the inner housing or shell 14 of the ejector 15 is bodily displaced 20 against the resistance of the helicoidal spring 14 longitudinally of and within the tube when the outer concentrically arranged tubular bushing 16 is slidably moved in a similar direction outside of the tube. For this purpose, a driving pin 25 is utilized. This pin extends diametrically through and is fixed to the shell 14 to drive the latter and has ends 26 fastened to the exterior sleeve 16 of the ejector. These ends 26 are rectilinearly guided in diametrically opposed slots 27 extending longitudinally of tube 10 and the walls of slots 27 cooperating with ends 26 prevent rotation of the ejector as is well understood. The rear walls of the ends of these slots 27 serve to limit retraction or rearward displacement of the 35 ejector at which time the rear rim 23 of the bushing 16 is contiguous to the pivoted ears 24 of the cover 12. Thus, by the arrangement disclosed, the ejector if fully retracted is held against longitudinal displacement when the hair clamping complements 10 and 12 are in a closed relation.

Projecting in part into the front end of tube 10 and in part overhanging the latter is a rotatable closure generally identified 28. Specifically closure 28 includes an expanded cylindrical part 29 rotatably confined within the bearing defined by the front end of the tube 10 by inwardly turned lugs 30 and by the terminal inwardly turned annular lip 31 formed at the exterior forward end of the tube.

The reduced part or stem 30' of closure 28 may be said to be of substantially frusto-conical configuration and is provided at its most flared portion with a rounded corner 32. As shown 55

closure 28, which in fact is a support for rotatably sustaining the curler, includes the axially arranged bore 33 adapted to slidably receive the rectilinear shank 34 of a normally closed spring 5 metal hair pin 35 of the type well known in the art.

It will be noted that if shank 34 of the hair pin is inserted into the closure 28 the flared portion of the stem 30' constitutes means for diverging shank 36 of the hair pin away from its companion shank 34 against the resilient resistance offered by the closed end 45 of the hair pin. Having positioned the hair pin on the curler and in the manner indicated in Fig. 1, the hair pin is now ready and waiting for the curl to be formed by the curler.

If therefore manipulator 37 carried by the rear end of the cover 12 be depressed against the resistance of spring 21, the forward end of the cover is raised. Thus a gap is provided between the cover and tube of the curler to admit a part of a tress of hair 38. Removal of finger pressure from manipulator 37, causes the forward end of the cover to clamp the inserted hair against the tube. It should be observed however that preparatory to the insertion of hair which is to be curled about the tube and cover the ejector 15 is in its fully retracted position and is maintained in such retracted position by spring 14' having one end appropriately fixed to the fulcrum pin 11 and the other end fastened to driving pin 25.

Now with the hair pin in its waiting and open relation and with a part of the tress clamped between the cover and tube, the user grasps stem 30' of the closure 28 and rotates the curler, that is, both the tube and cover rotate relative to closure 28. It follows that the clamped tress of hair is wound about the tube and cover forming the curl 39 and to facilitate such rotation a handle or extension is provided in the form of a comb 40 which has a reduced cylindrical part or plug 41 fitting snugly into bore or socket 42 and positively held therein by the rivet 43.

Having completed the winding operation, flange 17 is grasped and shifted towards the front part of the curler and spring 14' starts to expand. The ejector 15 now has a dual function. First the rim 20 thereof constitutes lifting means to slightly raise the cover. Specifically rim 20 strikes the inclined or cam part 19 of the cover. Hence the front part of the cover is lifted, thus releasing the clamping pressure on the hair formerly clamped between the tube and cover in order to facilitate proper transfer of the curl 39 from the curler when the ejector is moved towards the front of the curler.

Secondly, if the ejector is moved along the tube after the clamping action of the cover is released flange 17 ultimately meets the rear end of the curl 39, and the curl is therefore shifted or transferred along the outside of the tube. However since flange 17 is in advance of the inner shell 14 the transferred curl will be over the front end of the tube and the rotatable closure 28 before the closed end 14" of the shell or plug 14 meets terminal 44 of the shank 34 in which event the hair pin is bodily slidably displaced or shifted automatically longitudinally of the tube 70 and when shell 14 reaches the limit of its stroke when moving in a direction towards the front end of the curler, that is, when it strikes stop lugs 30 of the tube, curl 39 will be fully discharged from the curler and automatically falls 75 and becomes threaded onto projected rectilinear

shank 34 as illustrated in Fig. 6. In other words, as the ejector 15 moves towards the rotatable closure 28 it serves to progressively displace the curl bodily due to flange 17 and also causes the pin to be displaced or projected bodily at a later time after the curl reaches the front end of the curler due to the action of the closed end 14" of shell 14 to automatically discharge the curl onto the waiting hair pin which when removed from closure 28 automatically closes to clamp the 10 curl threaded on one of its shanks.

Stated in another way by the present arrangement, it is apparent that the ejector automatically threads the curl onto a projected portion of one shank of the bobby pin to permit the curl ejected to be arranged between the shanks of this pin and when the latter is now removed from the rotatable closure 28 the outer shank 36 automatically shifts towards the curl threaded onto the companion shank 34 due to the inherent 20 resilient action of the loop 45 which tends to normally hold the shanks in a closed relation.

However it should be observed that pursuant to the displacement of the ejector to thread the curl formed onto one end of the shank of the hair pin and if finger pressure be removed from flange 17 of the curl transfer or driving means 15, the latter is automatically retracted due to the compression of spring 14. Thus the ejector is held normally retracted and the cover is normally held closed for during retraction of the ejector the latter moves rearwardly of the front part of the cover and spring 21 holds the front part of the cover against the exterior surface of tube 10.

In the broader aspects of the invention, I do not desire to be understood as limiting the embodiment thereof to details herein shown illustratively as a wide variety of modifications may be made within the scope of the invention.

I claim:

1. In combination, hair curling means, a hair pin, means at one end of said curling means and rotatable relative to the latter for separating the shanks of said hair pin, and means slidably longitudinally of said hair curling means for automatically threading a curl on said curling means on one of said shanks.

2. In combination, hair curling means, a closure carried by said curling means, a hair pin having normally closed shanks adapted to be separated by said closure, and means slidably and rectilinearly carried by said curling means for transferring a curl from the latter on said hair pin.

3. In combination, a hair pin, hair curling means rotatable relative to said pin and for curling hair and having means for rotatably sustaining said curling means and for separating the shanks of said pin, and slidable means mounted on and shiftable lengthwise of said curling means for transferring a curl from the latter onto one shank of said pin.

4. In combination, a hair pin, hair curling means rotatable relative to said pin and for curling hair and having means for separating the shanks of said pin, and means carried by and slidably lengthwise of said curling means for discharging a curl from said curling means onto one shank of said pin.

5. In combination, a hair pin, hair curling means rotatable relative to said pin and for curling hair and having means for separating the shanks of said pin, and an ejector carried by and slidably guided lengthwise of said curling means

to discharge a curl from said curling means onto one shank of said pin.

6. In combination, a hair pin, curling means rotatable relative to said pin and for curling hair and having means at one end thereof for separating the shanks of said pin, and an ejector slidably guided on and longitudinally of said curling means and including means for shifting a curl on said curling means therefrom, and means carried by and movable longitudinally of said curling means for projecting a part of said pin to threadably receive said curl shifted from said curling means.

7. In combination, a hair pin having normally closed shanks, hair curling means, means for spreading said shanks, and ejector means comprising an exterior member for shifting a curl on said curling means and an interiorly disposed member for projecting one of said shanks to threadably receive the curl shifted from said curling means.

8. In combination, a hair pin having normally closed shanks, hair curling means, means for spreading said shanks, and ejector means comprising advanced and rearwardly disposed means for shifting a curl longitudinally of said curling means towards said pin and for projecting said pin to, permit one of said shanks to threadably receive the curl shifted from said curl.

9. In combination, a hair pin having normally closed shanks, hair curling means, means for spreading said shanks, an ejector displaceable longitudinally of said curling means towards one end of the latter for shifting a curl on said curling means and for discharging said curl therefrom onto one shank of said pin, and automatically controlled means for retracting said ejector.

10. In combination, a handle having toothed means, a hair pin, hair curling means secured to said handle, a support carried at one end of said hair curling means to spread the shanks of said pin, an ejector displaceable in a direction longitudinally of said handle and of said curling means to remove a curl from the latter, and means upon displacement of said ejector for projecting at least one shank of said pin to threadably receive the curl removed from said curling means.

11. In combination, a hair pin having normally closed shanks, hair curling means having means for supporting said pin and for diverging said shanks, ejector means slidably associated with said curling means for slidably displacing a curl from said curling means, and means for automatically projecting said pin longitudinally of said curling means to receive said curl on its removal from said curling means.

12. In combination, hair curling means comprising an elongated body and a pivoted cover for clamping a portion of a tress of hair to be wound about said body and cover to form a curl, spring means cooperating with said cover to hold the latter in pressure engagement against said portion, and means displaceable longitudinally of said body for actuating said cover to release said pressural engagement.

13. In combination, an elongated body, a cover pivoted to said body and including a cam, an ejector slidably mounted on said body for actuating said cam to release a portion of said cover from a part of a tress of hair interposed between said cover and body.

14. In combination, an elongated body, a cover pivoted to said body including an intermediately disposed cam, and means slidably mounted on said body for actuating said cam to release pres-

sural engagement imparted by said cover on a part of a curl against said body and for removing said curl from said body subsequent to the release of said pressural engagement.

15. In combination, an elongated body, a cover pivoted to said body including an intermediately disposed cam, a normally retracted curl ejector slidably mounted on said body and movable towards one end of the latter for actuating said cam to release pressural engagement imparted by said cover on a part of a curl against said body and for removing said curl from said body subsequent to the release of said pressural engagement, and means for automatically retracting said ejector pursuant to the removal of said curl from said body.

16. In combination, a hair curler, a normally closed hair pin, means for holding the shanks of said pin separated, an ejector movably carried by said curler and having a flange for removing a curl from said curler, and means within said curler for projecting a part of said pin to threadably receive the removed curl.

17. In combination, a hair curler, a normally closed hair pin, means rotatably sustained by said curler for holding the shanks of said pin separated to wait for a curl on said curler, and an ejector slidably mounted on said curler comprising an exteriorly disposed member for bodily shifting said ejector longitudinally of said curler to remove a curl from the latter, and a member movable longitudinally of and within said curler for projecting a portion of said pin to automatically receive the curl removed from said curler.

18. In combination, a hair curler, a normally closed hair pin, means rotatably sustained by said curler for holding the shanks of said pin separated and diverged to wait for a curl on said curler, a normally retracted ejector slidably mounted on said curler comprising an exteriorly disposed member for bodily shifting said ejector longitudinally of said curler to remove a curl from the latter and comprising an interiorly arranged member within said curler for projecting a portion of said pin out of said rotatable means to receive the curl removed from said curler, and spring means for automatically retracting said ejector.

19. Hair curling means, waiting means, and concentrically arranged slidable means on said curling means for removing a curl from said curling means, and means within said curling means for actuating said waiting means to receive the curl removed from said curling means.

20. In combination, a hair pin having normally closed shanks, hair curling means rotatable relative to at least one of said shanks and having means for spreading said shanks, and an ejector movably carried by and displaceable longitudinally of said curling means for shifting a curl on said curling means towards and over one of said shanks to threadably receive the curl shifted from said curling means.

21. In combination, a handle having toothed means, a hair pin, hair curling means secured to said handle, a member rotatably sustaining said curling means and having means for spreading the shanks of said pin, an ejector mounted on said curling means and displaceable in a direction longitudinally of said handle and of said curling means to remove a curl from the latter, and means responsive to the displacement of said ejector for projecting at least one shank of said pin longitudinally of said curling means to

threadably receive the curl removed from said curling means.

22. In combination, a hair pin having normally closed shanks, supporting means for spreading said shanks, hair curling means rotatably sustained by said curling means, ejector means associated with said curling means for displacing a curl from said curling means, and means for automatically projecting said pin longitudinally 10 of said curling means to permit one of said shanks to receive said curl on its removal from said curling means.

23. In combination, hair curling means comprising an elongated body and a pivoted cover for clamping a portion of a tress of hair to be wound about said body and cover to form a curl, spring means cooperating with said cover to hold the latter in pressural engagement against said portion, and means displaceable longitudinally 15 of said body for actuating said cover to release said pressural engagement and for removing the curl from said curling means.

24. In combination, an elongated body, a cover

pivoted to said body and including a cam, an ejector slidably interposed between said body and cover for actuating said cam to release a portion of said cover from a part of a tress of hair interposed between said cover and body and for removing a curl from the latter, and means to limit 5 slidable displacement of said ejector.

25. In combination, a hair curler having a longitudinally disposed slot, a normally closed hair pin, means rotatably sustained by said curler 10 for holding the shanks of said pin separated to wait for a curl on said curler, and an ejector having means slidably guided by the walls of said slot and comprising an exteriorly disposed member for bodily shifting a curl longitudinally 15 of said curler to remove said curl from the latter, a member movable lengthwise of said slot and within said curler for projecting a portion of said pin to automatically receive the curl removed from said curler, and means to limit displacement of said ejector relative to said curling means.

NATHAN L. SOLOMON.
